CAGE FOR A POPCORN POPPER

Robert Gottlieb, New York, N.Y., assignor to Argo
Industries Corporation, Jackson Heights, N.Y.

Filed Mar. 25, 1970, Ser. No. 22,056

Term of patent 14 years

Int. Cl. D7—02

U.S. Cl. D44—1

FIG. 3.

FIG. 1 is a perspective view of a cage for a popcorn popper showing my new design;

FIG. 2 is a left side elevational view;

FIG. 3 is a bottom view of the cage for a popcorn popper as shown in FIGS. 1 and 2.

I claim:

The ornamental design for a cage for a popcorn popper, as shown.
